UNITED STATES PATENT OFFICE.

EDWIN GEORGE L. Langley, of North Hadley, Massachusetts.

POSTAGE-STAMPER.

1,277,323.

Specification of Letters Patent. Patented Aug. 27, 1918.

Application filed May 4, 1917. Serial No. 166,413.

To all whom it may concern:

Be it known that I, EDWIN GEORGE L. Langley, a subject of the King of Great Britain, residing at North Hadley, in the 5 county of Hampshire and State of Massachusetts, have invented certain new and useful Improvements in Postage-Stampers; and do hereby declare the following to be a full, clear, and exact description of the 10 invention, such as will enable others skilled in the art to which it appertains to make and use the same.

This invention relates to improvements in a postage stamper and more particularly to 15 a machine for applying postage stamps to letters or the like and has for one of its objects, the provision of a device of the above stated character, which is capable of permitting a letter to be inserted in the machine and upon operating the machine, a stamp will be applied and affixed thereto.

Another object of this invention is to provide means for automatically stopping the 20 operation of the machine after a stamp has been applied to a letter and the machine has completed a single operation.

A further object of this invention is the provision of means for setting the automatic 25 stopping means prior to the operation of the machine, thus preventing the application of more than one stamp upon a letter by continuing the operation of the machine after a single operation has been completed.

A further object of this invention is to 30 provide a novel form of stamp applying roller, which will receive the stamp from a feeder and moisten the same and deposit it upon a letter.

A further object of this invention is to 35 provide means for compressing the letter and stamp against the stamp applying roller so that the stamp will be thoroughly affixed to the envelop.

A further object of this invention is the 40 provision of means, which will grip and hold a stamp upon the stamp applying roller, and which will automatically release the stamp so that the same may be applied to the letter.

50 A still further object of this invention is the provision of a postage stamper of the above stated character, which shall be simple, durable and efficient, and which may be manufactured and sold at a comparatively low cost.

With these and other objects in view as

will become more apparent as the description proceeds, the invention consists in certain novel features of construction, combination and arrangement of parts as will 60 be hereinafter more fully described and claimed.

For a complete understanding of my invention, reference is to be had to the following description and accompanying drawings, in which:

Figure 1 is a front elevation partly in section of a postage stamper constructed in accordance with my invention,

Fig. 2 is a rear elevation partly in section 70 of the same,

Fig. 3 is a longitudinal sectional view illustrating the means of applying the stamps to the stamp applying roller,

Fig. 4 is a fragmentary longitudinal sectional view of the means for automatically stopping the operation of the machine after a single operation thereof,

Fig. 5 is a fragmentary detail sectional view of the automatic stopping means,

Fig. 6 is an end elevation of the automatic means for operating the automatic stopping means,

Fig. 7 is an end elevation partly in section 80 of the stamp applying roller illustrating the means of securing the stamps to the roller,

Fig. 8 is a perspective view of the stamp feeding hopper,

Fig. 9 is a detail sectional view of a gage for indicating the amount of water within 90 the water tank of the machine,

Fig. 10 is a perspective view of a member for connecting the letter carrier and compressor to a cam,

Fig. 11 is a detail sectional view of the 95 hopper illustrating the inwardly directed flanges for retaining stamps therein.

Referring in detail to the drawings, the numeral 1 indicates a casing having a bottom or base 2, on which is secured a pair 100 of relatively spaced supporting members 3. The supporting members 3 have slidably mounted upon the longitudinal upper edges, presser boards 4 and 5. The presser board 4 is disposed over the board 5 and has its 105 front edge hinged to the front edge of the lower presser board 5 as illustrated at 6 for permitting the presser board 4 to move in relation to the presser board 5. Plates 7 are secured to the rear end of the presser board 4 and upon the under face thereof and have 110 formed thereon, downwardly depending

guide pins 8, which are slidably received within plates 9 secured to the lower presser board 5, whereby the rear end of the presser board 4 is supported in an elevated position 5 with relation to the rear end of the presser board 5 and which permits the presser board 4 to move in the direction of the presser board 5 during the operation of the machine.

Vertically disposed supporting standards 10 are arranged adjacent the front ends of the supporting members 3 and slidably support the arm portions 11 of a substantially U-shaped member 12. The web portion 13 of the U-shaped member 12 is located adjacent the rear ends of the supporting members 3 and has an arm 14 formed thereon adjacent one of its arm portions as clearly shown in Fig. 10. The arm 14 has journaled to its free end a roller 15, which travels in an eccentric groove 16, which is formed within a wheel 17. The wheel 17 is journaled upon a shaft 18 carried by vertically disposed standards 19 that are secured to the base or bottom 2 of the casing 1, as shown 25 at 20.

A shaft 21 is journaled in the supporting members 3 and has mounted thereon, a pulley 22 on which a belt 23 travels. The belt 23 is mounted upon a pulley 24, which is 30 secured to the shaft 18, whereby upon rotating the shaft 21, the shaft 18 will be driven thereby, rotating the wheel 17 and reciprocating the substantially U-shaped member 12 on the supporting standards 10. 35 The arm 14 formed upon the substantially U-shaped member 12 is slidably mounted adjacent the wheel 17 in a vertically disposed supporting standard 26, which is secured to the base or bottom 2 of the casing as shown 40 at 27.

Plates 28 are secured to the ends of the arm portions of the substantially U-shaped member 12 and are vertically disposed as clearly shown in Figs. 1 and 3 and have 45 formed therein, elongated slots 29, which receive links 30 carried by the front end of the presser board 5 for sliding the presser boards 4 and 5 upon the supporting members 3 when rotation of the shaft 18 is made 50 by the shaft 21. A suitable letter guard 31 is secured to the upper face of the presser board 4 and is adapted to receive and guide letters upon the presser board 4 received by way of the opening 32 in the casing 1.

55 A main drive shaft 33 is journaled within the casing 1 and has one end thereof disposed exteriorly of the casing to which is secured, a crank handle 34 for rotating the drive shaft. The drive shaft 33 has secured 60 thereto, a gear 35 which meshes with the gear 36 carried by the shaft 21, whereby upon rotation of the drive shaft 33, by the crank handle 34, the shaft 21 will be driven through the gears 35 and 36.

65 An elliptical stamp applying roller 37 is

eccentrically mounted upon the drive shaft 33 as shown in Fig. 7. The roller 37 is provided with a raised portion 38 for the purpose of forming a seat or rest for a postage stamp. The roller 37 is provided with a 70 groove or recess 39 adjacent the raised portion 38 in which is mounted a gripper 40. The gripper 40 is hinged to the roller 37 as shown at 41 and has formed upon its free edge, teeth 42, that are adapted to normally 75 rest upon a metallic strip 43 embedded within the roller 37 to prevent the teeth from biting in to or injuring the roller. The gripper 40 has a spring 44 connected thereto at one thereof and has its opposite end connected to the roller 37 as shown at 45 for the purpose of normally holding the gripper 40 in a closed position or seated within the recess or groove 39. The gripper 40 is adapted to receive and hold a postage stamp upon the raised portion 38 with the mucilage side of the stamp turned upwardly.

The postage stamp is received from a hopper 46 in which is stored a plurality of postage stamps as shown at 47. The hopper 46 has formed thereon, a threaded bolt 48 which is adjustably secured to a supporting beam 49 by means of a nut 50. The supporting beam 49 is supported by the casing in an inclined position as shown in Fig. 4 for the 90 purpose of supporting the hopper 46 in an inclined position in respect to the stamp applying roller 37. The hopper 46 is provided with an outlet chute 51 upon its front wall adjacent its lower end, and is adapted to receive one postage stamp at a time from the hopper, the postage stamp being held against accidental displacement upon the chute 51 by resilient arms 52, which are carried by the front wall of the hopper and have their free ends disposed at a point beyond the end of the chute 51, the end of the chute 51 being disposed adjacent the periphery of the stamp applying roller 37 so that the postage stamp may be put upon the raised portion 38 and held thereon by the gripper 40. The bottom wall of the hopper 46 is open and has formed upon its longitudinal edges inwardly directed flanges 53 for the 95 purpose of supporting the stamps 47 within the hopper 46. The upper hopper end of the hopper 46 is closed by a removable cover 54, which has secured to its under face an expansion spring 55 carrying a follower 56, which urges the stamps 47 downwardly 100 within the hopper. A shaft 57 is journaled in the casing 1 and is disposed directly under the hopper 46 and has mounted thereon, a drum 58 provided with a plurality of teeth 59 for the purpose of engaging the lowermost stamp within the hopper 46 and shoving the same outwardly upon the chute 51 and on to the raised portion 38 of the stamp applying drum 37. The shaft 57 has mounted thereon, a pulley 60, which carries a belt 105

100

95

105

110

115

120

125

130

61 mounted upon a pulley 62 carried by the drive shaft 33, whereby upon rotation of the drive shaft 33, the shaft 57 will be rotated, causing the teeth 59 upon the drum 58 to move the lowermost stamp within the hopper 46 on to the raised portion 38 of the stamp applying roller.

5 An arm 63 is secured to one end of the gripper 40 and has mounted upon its free 10 end, a roller 64 adapted to travel about the periphery of a cam 65, which is rigidly supported adjacent one end of the stamp applying roller 37 by a support 66. The roller 64 travels about the periphery of the cam 65 15 and will cause the gripper 40 to open and release the stamp as the raised portion 38 bearing the stamp moves adjacent the rear end of the presser board 4, so that the stamp will be deposited upon the letter.

20 The cam 65 is of such a shape that it will hold the gripper open from a point after it has deposited the stamp upon the letter upon the presser board 4 until another stamp has been applied or positioned upon the raised 25 portion 38 whence the gripper 40 moves to a closed position, the teeth thereon engaging the stamp and holding the same firmly upon the raised portion 38.

A locking member 67 is slidably mounted 30 upon a supporting block 68 carried by the casing 1 by means of a pin 69 extending through a slot 70 in the locking member. One end of the locking member 67 is enlarged as shown at 71 and has formed there- 35 on a curved extension 72 that is slidably mounted within an elongated slot 73 in a support 74 carried by the casing 1. The other end of the locking member 67 is reduced to form a locking extension 75, which 40 is adapted to be received within a recess 76 formed within a disk 77 that is mounted upon the drive shaft 33, whereby the drive shaft is held against rotation. A support 78 is carried by the casing to which is con- 45 nected a spring 79 that is received within an ear 80 mounted upon the enlarged end 71 of the locking member 67, whereby the locking member 67 is slid upon the support 68 so that the locking extension 75 will en- 50 gage the periphery of the disk 77 at all times and which will pass into the recess 76 when said recess moves in registration with the locking extension 75 so that the shaft 33 will be locked against rotation.

55 An operating rod 81 is slidably mounted within an elongated slot 82 of the locking member 67 as shown at 83. The opposite end of the operating rod 81 is pivoted to an operating lever 84 as shown at 85. The operating lever has formed upon its outer end, a handle 86, which is disposed exteriorly of the casing 1 by way of an elongated slot 87. The lower end of the operating lever 84 is permanently secured to an automatic release 60 65 88 as shown at 89. The automatic release 88

is pivoted to the cam 65 as shown at 90. A coiled spring 91 is connected to the operating lever 84 and to the casing for normally holding said operating lever in a rearward direction so as to permit the locking extension 75 upon the locking member 67 to remain in the notch 76 of the disk 77, thereby holding the machine against operation.

70 The releasing member 88 has formed thereon, an extension 92, which is adapted 75 to be received within a notch 93 of a catch 94 that is pivoted to the cam 65 as shown at 95. By swinging the operating lever 84 forwardly, by the handle 86, the locking extension 75 is withdrawn from the disk 77 80 freeing the drive shaft so that the machine may be operated. As the operating lever 84 moves forwardly, it swings the automatic releasing member 88 into an engagement with the catch 94 locking said automatic releasing member in a closed position as shown in Fig. 4. The catch 94 is spring pressed by a spring 96 so as to retain the catch into engagement with the tongue 92 of the automatic releasing lever 88. When the catch 90 94 and the automatic releasing member 88 are moved into engagement with each other or in a locked position, the outer edges of the catch 94 and the automatic releasing member conform to the contour of the cam 95 65 so that upon the roller 64 traveling about the cam 65 it will not be interfered with by the catch 94 and the automatic releasing member 88.

85 A pin 97 is secured to the one end of the 100 stamp applying roller 37 and is adapted to engage the lug 98 upon the catch 94 to release the catch 94 from engagement with the automatic releasing member 88. The pin 97 engages the projection or lug 98 upon the catch when the machine has completed a single 105 stamp applying operation so that the automatic releasing member 88 will swing to an open position as shown in Fig. 6, permitting the lever 84 to move rearwardly under the influence of the spring 91 which causes the operating rod 81 to move rearwardly permitting the spring 79 to force the locking member 67 to slide upon the supports 68 and 73, permitting the locking extension 75 to move 110 into the recess 76 of the disk 77, locking the machine against operation, thus it will be noted that it is necessary to move the operating lever 84 forwardly before the machine can be operated so as to release the locking 115 member 67 from the disk 77.

120 A pair of cams 99 are secured to the shaft 21 and are adapted to engage the presser board 5 for raising the presser boards 4 and 5 upwardly when the stamp has been applied to the letter for the purpose of compressing the stamp and letter against the roller 37, causing the stamp to thoroughly adhere to the envelop.

125 A tank 100 is secured within the casing 130

and has the front wall thereof disposed adjacent the rear ends of the presser boards 4 and 5. The tank 100 is adapted to contain water and has mounted therein, a perforated 5 cylindrical member 101, which slidably supports a float 102. The float 102 has secured thereto, a vertically disposed rack bar 103, which meshes with a gear 104. The gear 104 is secured to a stub shaft journaled in 10 the casing and to which is secured an indicating hand 105. An arcuate shaped plate 106 is carried by the casing adjacent the indicating hand 105 and has applied thereon, a suitable scale as clearly shown in Fig. 9, 15 whereby the amount of water contained in the tank 100 may be readily determined by the indicating hand 105 indicating to the scale upon the arcuate shaped member 106.

A shaft 107 is journaled in the casing 1 20 and extends through the tank 100 and has mounted thereon, a moistening roller 108. The moistening roller 108 is adapted to apply water or moisture upon the adhesive side of the stamp as the same travels with 25 the stamp applying roller 37 upon the raised portion 38 thereof, so that when the stamp is applied to the letter upon the presser board 4, the adhesive material on the stamp is moistened so that the same will readily 30 adhere to the letter. The shaft 107 has secured thereto a pulley 109 on which is mounted a belt 110. The belt 110 passes over a pulley 111 carried by the drive shaft 33, whereby upon rotation of the drive shaft 33, the moistening roller 108 will be rotated, 35 supplying moisture to the stamps carried by the stamp applying roller 37.

The supporting beam 49, which supports the hopper 46 is adjustably secured to the 40 casing 1 by brackets 112, whereby the hopper 46 may be moved toward and from the stamp applying roller 37 as desired.

In operation, the operating handle 86 is pulled forwardly disengaging the locking 45 member 67 from the notch 76 of the disk 77, freeing the drive shaft 33. As the operating lever 84 is moved forwardly, the automatic releasing member 88 is moved into engagement with the catch 94 and held in a locked 50 position. The drive shaft 33 is then rotated and a stamp is placed upon the raised portion 38 of the roller 37 by the drum 58. At this point, the grippers are opened and 55 upon further rotation of the drive shaft 33, the grippers move into closed position permitting the teeth thereon to grip and hold the postage stamp upon the raised portion 38. As the roller 37 rotates with the drive shaft 33, the stamp moves in the direction 60 of the presser boards 4 and 5, and as the stamp reaches the presser boards, the cam 65 opens the gripper and permits the postage stamp to be applied to the letter. The letter is placed upon the presser board 5 and 65 against the front wall of the tank 100 by

way of the opening 32 in the casing 1. Upon further rotation of the shaft 33, the arm 63 follows the curvature of the cam 65, holding the gripper open until another stamp has been applied to the raised portion 38, 70 this other stamp being applied to the raised portion 38 after the shaft 33 has completed a single revolution or upon another operation of the machine. Upon the shaft 33 completing a single revolution, the pin 97 75 80 engages the lug 98 upon the catch 94, freeing the automatic releasing member 88, which permits the locking member 67 to engage the notch 76 in the disk 77 and locks the drive shaft 33 against further rotation, thus preventing more than one stamp to be applied to a letter upon a single operation of the machine. Immediately upon pulling the operating lever 84 forwardly, the machine is again ready to apply another stamp upon 85 the same or another letter. As the stamp is applied upon the letter the presser boards are raised upwardly by the cams 99 compressing the letter and stamp against the stamp applying roller 37. The presser 90 boards 4 and 5 then move rearwardly in the direction of the opening 32 by means of the wheel 17 so that the letter may be readily reached by the operator and removed from the presser boards. 95

While I have shown and described the preferred embodiment of my invention, it will be understood that minor changes in construction, combination and arrangement of parts may be made without departing 100 from the spirit and scope of the invention as claimed.

Having thus described my invention, what I claim is:

1. A stamp applying machine comprising 105 a casing, a letter supporting means within said casing, an elliptical stamp applying roller eccentrically mounted within said casing, means for depositing stamps upon said roller, and means for holding said stamps 110 upon the roller prior to applying them to letters.

2. A stamp applying machine comprising a casing, a letter supporting means within said casing, a stamp applying drum journaled in said casing, a hopper carried by said casing, a chute formed on said hopper and located adjacent the roller, spring fingers carried by said hopper and adapted to engage the stamps as they pass over the 120 chute, and means for dispensing the stamps from the hopper on to the drum.

3. A stamp applying machine comprising a casing, a letter supporting means located within said casing, a stamp applying roller 125 journaled within said casing and adapted to apply a stamp on a letter carried by said letter supporting means, a hopper adjustably secured to the casing and adapted to deposit stamps upon the stamp applying 130

roller upon a complete revolution thereof and means locking the roller after a complete revolution.

4. A stamp applying machine comprising 5 a casing, a letter supporting means within said casing, a shaft journaled in said casing, a stamp applying roller carried by said shaft, means for depositing stamps upon the roller, a gripper carried by said roller 10 and adapted to engage the stamps, a cam secured within said casing, means carried by the gripper and engaging the cam for disengaging the gripper from the stamp prior to applying the stamp to a letter, and 15 means for locking the shaft against rotation.

5. A stamp applying machine comprising 20 a casing, a letter supporting means within said casing, a drive shaft journaled within said casing, a stamp applying roller carried by said shaft, means for applying stamps to said roller, a gripper carried by said roller and adapted to retain a stamp upon said roller, a cam secured to said casing, means carried by the gripper and engaging the cam 25 for releasing the gripper from the stamp prior to applying the stamp to a letter, a locking means located within said casing and adapted to lock the drive shaft against rotation, and means for releasing said last 30 named means.

6. A stamp applying machine comprising 35 a casing, a letter supporting means carried by said casing, a drive shaft journaled in said casing, a stamp applying roller carried by said shaft, means for supplying stamps to said roller, means for holding stamps upon said roller, a cam secured to said casing and adapted to release the last named means from the stamps, a locking means located 40 within said casing, a disk secured to the drive shaft and having a notch adapted to receive the locking means to hold the drive shaft against rotation, and means for disengaging the locking means from the disk to 45 free the drive shaft.

7. A stamp applying machine comprising 50 a casing, a drive shaft journaled in said casing, a stamp applying roller carried by said shaft, means for depositing stamps upon said roller, a locking member slidably mounted within said casing, a disk secured to said shaft having a notch therein and adapted to receive the locking member to hold the shaft against rotation, means for 55 disengaging the locking member from the notch in the disk to free the shaft, and an automatic means for releasing the last named means to permit the locking member to engage the notch of the disk to lock the shaft 60 against rotation after a complete revolution of the stamp applying roller.

8. A stamp applying machine comprising 65 a casing, a letter supporting means within said casing, a drive shaft journaled in said casing, a stamp applying roller journaled

in said casing, means for supplying stamps to said roller, a cam secured in said casing, a cam secured to the shaft and having a notch therein, a locking member slidable in said casing, means for urging the locking member in engagement with the notch in the disk, and an operating lever carried by the first named disk and connected to the locking member to disengage it from the second named disk to free the drive shaft. 75

9. A stamp applying machine comprising 80 a casing, a letter supporting means within said casing, a drive shaft journaled in said casing, a stamp applying roller carried by said casing, means for supplying stamps to said roller, a disk secured to said shaft and having a notch therein, supporting brackets secured to said casing, a locking member slidably mounted on said supporting brackets, a locking extension formed on said locking member and adapted to be received within the notch of the disk, a spring for urging the locking member in the direction of the disk, and an operating lever for disengaging the locking member from the disk. 90

10. A stamp applying machine comprising 95 a casing, a letter supporting means within said casing, a drive shaft journaled in said casing, a stamp applying roller carried by said shaft, means for applying stamps to said roller, a cam secured to the casing, a locking member slidable in said casing and adapted to hold the shaft against rotation, and an automatic releasing member carried by said cam, an operating lever carried by said automatic releasing member and connected to the locking member, means for locking the automatic releasing member in a closed position upon forward movement of the lever to release the locking member from the shaft, 105 and means for automatically releasing the automatic releasing means upon a complete rotation of the roller.

11. A stamp applying machine comprising 110 a casing, a letter supporting means within said casing, a drive shaft journaled in said casing, a stamp applying roller carried by said shaft, means for applying stamps to said roller, a cam secured to said casing, a locking means located in said casing and 115 adapted to hold the shaft against rotation, an automatic releasing member carried by said cam, a catch carried by said cam, an operating lever carried by the automatic releasing member and connected with the locking means and adapted to move the automatic releasing member into engagement with the catch upon releasing the locking means from the shaft, and a lug carried by 120 said roller and adapted to engage the catch 125 to release the automatic releasing means to permit the locking means to lock the shaft against rotation upon a complete revolution of the roller.

12. A stamp applying machine comprising 130

a casing, a letter supporting means within said casing, a stamp applying roller journaled in said casing, means for supplying stamps to said roller, means for moistening 5 said stamps upon said roller, and means for compressing the stamp and letter against the stamp applying roller after the stamp has been applied to said letter.

13. A stamp applying machine comprising 10 a casing, a letter supporting means within said casing, a stamp applying means within said casing, a tank located within said casing, means for supplying moisture from the tank to the stamps, a perforated cylindrical 15 member located within said tank, a float slidable in said cylindrical member, a rack bar secured to said float, a stub shaft secured to said casing, an arcuate shaped member having the tail thereon located adjacent 20 the stub shaft, a gear journaled on said stub shaft, and in mesh with the rack bar, and an indicating hand secured to the gear and adapted to register the amount of water within the tank upon the gear on the arcuate 25 shaped member.

14. A stamp applying machine comprising a casing, supporting members within said casing, presser boards carried by said members and adapted to receive letters, a 30 stamp applying roller within said casing and adapted to apply stamps to the letters on said presser boards.

15. A stamp applying machine comprising a casing, supporting members within said 35 casing, spring pressed presser boards carried by said supports, means for reciprocating said boards, and a stamp applying roller journaled in said casing and adapted to apply stamps upon letters upon the presser 40 boards.

16. A stamp applying machine comprising a casing, supporting members within said casing, a presser board slidable on said members, a presser board hinged to the first 43 named presser board and receiving letters, means for movably supporting the rear ends of the presser boards apart, and a stamp applying roller journaled in said casing and adapted to apply stamps on the letters carried by the second presser board.

17. A stamp applying machine compris-

ing a casing, supporting members within said casing, presser boards slidably mounted upon said supporting members, means for sliding said presser boards upon the supporting members, a stamp applying roller journaled in said casing, and means for raising the presser boards toward the stamp applying roller.

18. A stamp applying machine comprising a casing, supporting members within said casing, presser boards carried by said members, means for reciprocating said presser boards, a stamp applying roller journaled in said casing, and a cam for raising 65 the presser boards to exert pressure upon the letter and stamp against the stamp applying roller.

19. A stamp applying machine comprising a casing, supporting members within 70 said casing, a stamp applying roller journaled within said casing, presser boards mounted upon said supporting members, a substantially U-shaped member slidably mounted within said casing, and means for 75 connecting the arra portions of the substantially U-shaped member to the presser boards, and means for reciprocating the substantially U-shaped member to reciprocate the presser boards.

20. A stamp applying machine comprising a casing, presser boards slidably mounted within said casing, a stamp applying roller journaled within said casing, a substantially U-shaped member slidably mounted within said casing, means for connecting the ends of the arm portions of the substantially U-shaped member to the presser boards, an arm formed on the web portion of the substantially U-shaped member, a 80 wheel journaled within said casing, and having an eccentric groove, a roller carried by said arm and traveling in said groove, and means for rotating said wheel to reciprocate the presser boards.

In testimony whereof I affix my signature in presence of two witnesses.

EDWIN GEORGE L. LANGLEY.
